[57] CLAIM

The ornamental design for a containers carrier, as shown and described.

DESCRIPTION

FIG. 1 is a perspective view of a containers carrier, showing my new design;

FIG. 2 is a top view thereof, with the handles shown in an alternate position;

FIG. 3 is a front view thereof;

FIG. 4 is a bottom view thereof;

FIG. 5 is a side view thereof, the opposite side being identical; and,

FIG. 6 is a rear view thereof.

The broken line showing of containers in Figure 1 is for illustrative purposes only and forms no part of the claimed design.
